UNITED STATES PATENT OFFICE.

CHARLES T. BRADSHAW, OF WEST COLLINGSWOOD, NEW JERSEY.

LUBRICATING DEVICE.

Application filed June 14, 1921. Serial No. 477,393.

To all whom it may concern:

Be it known that I, CHARLES T. BRADSHAW, a citizen of the United States, residing at West Collingswood, in the county of Camden and State of New Jersey, have invented certain new and useful Improvements in Lubricating Devices, of which the following is a specification.

The object of my invention is to provide a lubricating device, for car wheel flanges, of novel, simple and efficient construction which may be readily thrown into an operative position, when desired, to supply a lubricant to the wheel flanges for the lubrication thereof and the track which they travel at curves, switches and other places where the lubrication is desired; and with this and related objects in view, the invention consists in the novel construction, combination and arrangement of parts hereinafter described and claimed.

In the accompanying drawings illustrating my invention,

Figure 1 is a side view of parts of a car having a lubricating device embodying my invention applied thereto.

Figure 2 is a view of the device and parts of a car as seen from one end of the car.

Figure 3 is a sectional detail of one of the pivoted members of the lubricating device and adjuncts.

Figure 4 is a detail of a part of one of the pivoted members and its supporting bracket as seen from a position at right angles to Fig. 3.

Figure 5 is a sectional detail of the oil guard and adjuncts, on line 5-5 of Fig. 3.

Figure 6 is a sectional detail of the pivoted member, on line 6-6 of Fig. 3.

Figure 7 is a sectional detail of the two way air valve, on line 7-7 of Fig. 2.

Figure 8 is a top view of the handle for operating the air valve.

Figure 9 is a sectional detail of the oil guard and adjuncts, on line 9-9 of Fig. 3.

Referring to the drawings, 2 designates a portion of the car body, 3 a portion of one of the trucks carrying the body 2, and 4 the forward pair of flanged wheels journaled in the truck 3. The truck 3 includes the usual cross bar 6 in advance of the forward wheels, and the construction and operation of the parts thus far described are common and well known and no detailed description or illustration thereof is deemed necessary herein.

Secured to the cross bar 6 adjacent to each wheel 4 is a bracket 7 having two spaced bearings 8 for the reception of the trunnions 9 of a member 10 which is arranged between the bearings 8 and pivotally supported by the bracket 7. The trunnions 9 are formed by a hollow shaft set in the member 10 and projecting from the respective sides thereof.

The member 10 comprises an arm 11 which extends downwardly from the trunnions 9 and an arm 12 which extends upwardly from the trunnions 9 and toward the wheel 4.

The lower end portion of the arm 11 carries an oil-containing vessel or box 13, and the upper end portion of the arm 12 carries a hollow guard 14 adapted to embrace the flange 15 of the wheel 4.

The arm 12 is of channel formation and carries an oil pipe 16 and an air pipe 17 seated therein and suitably secured thereto. The upper end of the air pipe 17 opens into the guard 14, and the upper end of the oil pipe 16 communicates with the air pipe 17 below the top thereof. The lower portion of the oil pipe 16 extends down into the oil box 13 and communicates therewith near the bottom thereof and the open lower end of the pipe 16 is guarded by a screen 18 to prevent dirt and foreign matter from passing with the oil from the box 13 into the pipe 16.

When compressed air is supplied to the lower portion of the pipe 17 and discharged from the upper end thereof into the guard 14, the air will draw oil from the box 13 up through the pipe 16 and discharge it therewith into the hollow guard 14 in the form of a spray; and the guard 14, embracing the flange 15, will receive the oil spray and confine it therein and direct it toward and spread it upon the flange 15 for the oiling or lubrication thereof.

During the travel of the wheel 4, its flange 15 enters and leaves the hollow guard 14 through openings in the end walls thereof, and the interior of the guard 14 is provided with suitable baffle walls or wings 19 spaced from its end walls 20 to prevent the oil spray from leaving the guard through its end openings.

The lower end of the air pipe 17 is connected by a suitable coupling 21 to a flexible pipe 22 which is connected to an air passage 23 formed in the body of the bracket 7 and leading to the top of a horizontally arranged, cylindrical opening 24 in the bracket 7. Slidably fitted within the open-

ing 24 is a cylindrical valve body 25, one end of which projects from the bracket 7 toward the arm 11, and the other end of which faces the open end of an air pipe 26 which is 5 screwed into the wall of the bracket 7 closing one end of the opening 24. When the valve 25 is in the position shown in Fig. 3, communication between the air pipes 22 and 26 is established through the opening 24, and, 10 when the valve 25 is moved past the passage 23 toward the pipe 26, communication between the pipes 22 and 26 is closed, for purposes hereinafter explained.

The air pipes 26 from the two brackets 15 7 lead to a two-way valve 28 on the car body 2, and the valve 28 is connected by a pipe 29 to a tank 30 carried by the car and containing compressed air which may be supplied to either of the pipes 26 by turning the valve 28. The stem 31 of the valve 28 is connected to a horizontal shaft 32 which forms a continuation thereof and is mounted to turn in bearings 33 secured to the bottom of the car body 2 and connected 20 by miter gears 34 to the lower end of a vertical shaft 35 which turns in bearings 36 on the dash board 37 of the car. The top of the shaft 35 is provided with a suitable handle 38 by means of which it may be turned. The construction of the valve 28 is such that when the handle 38 is in the central position the valve will be closed, and when the handle 38 is turned to the right, 25 air will be supplied from the tank 30 to the pipe 26 leading to the bracket 7 on the right, hand side of the car, and when the handle 38 is turned to the left, air will be supplied from the tank 30 to the pipe 26 leading to the bracket 7 on the left hand 30 side of the car.

The weight of the oil box 13 of each pivoted member 10 causes it to rest normally in the inoperative position shown by dot-and-dash lines in Fig. 3, with the arm 11 of the member 10 resting against the valve 25 which is thereby held back in the opening 24; and the member 10 is adapted to be moved back and forth from the inoperative position to the operative position, shown by 45 full lines in Fig. 3. When the member 10 is in the inoperative position, the hollow guard 14 is away from and out of contact with the wheel 4, and the air pressure from the tank 30 is not open to the valve opening 24. When, however, the valve 28 is turned to open communication between the tank 30 and the opening 24, the air pressure will 50 act upon the valve 25 and move it and the member 10 to the operative position shown by full lines in Fig. 3; and when the valve 28 is turned to stop the supply of compressed air to the pipe 26, the member 10 will drop back by gravity to the inoperative 55 position shown by dot-and-dash lines.

60 It will now be understood that when the

handle 38 is resting in the central position both pipes 26 will be out of communication with the compressed air tank 30, and that both members 10 and the parts carried thereby will be resting in the inoperative position away from the car wheels 4. This is the normal position of the parts when it is not desired to supply the lubricating oil to the wheels 4. When the car approaches a curved portion of the track turning to the left, it is desired to oil the flange of the forward wheel 4 on the right hand side of the car so that it may transmit the oil to the outside rail of the track for the reduction of friction between the rail and the forward wheel and the wheels of the car that follow it. Therefore, the handle 38 is turned to the right. This operation opens communication between the air pipe 26 on the right hand side of the car and the tank 30 and the compressed air supplied to the pipe 26 first acts upon the valve 25 and moves it and the member 10 controlled thereby to the operative position. The air then passes on through the passage 23 and pipes 22 and 17 to the guard 14 and draws oil from the box 13 and sprays into the guard 14 and the wheel flange embraced thereby and the supply of oil is continued as long as the handle 38 is held in the position toward the right hand side of the car. When the car has passed the curve, or when the supply of oil is no longer desired, the handle 38 is returned to the central position cutting off the supply of compressed air to the pipe 26 and thereby stopping the feeding of oil to the guard 14 and permitting the member 10 to drop back to the inoperative position.

When the car approaches a curved portion of the track turning to the right, it is desired to oil or lubricate the forward wheel flange 15 on the left hand side of the car which engages the outside rail of the right hand curve in the track; and, therefore, the handle 38 is turned to the left. This operation opens communication between the air pipe 26 on the left hand side of the car and operates the member 10 and parts carried thereby on the left hand side of the car for the lubrication of the wheel flange and the rail which it engages on the same side of the car, similarly to the operation of the member 10 on the right hand side of the car for the lubrication of the wheel and rail on that side.

It will thus be seen that the lubricating oil may be supplied to the forward carrying wheel on either side of the car by merely turning the handle 38 toward the side of the car where the lubrication is desired.

The width of that portion of each member 10 which extends between the bearings 8 of its supporting bracket 7 is less than

the space between the bearings to permit the member 10 to be moved laterally of the car relatively to the supporting bracket 7 when there is a side motion of the wheels

5 4 relatively to the supporting brackets 7.

The tops of the bearings 8 are made open, as shown in the drawings, to permit the easy removal of the trunnions 9 of the members 10 therefrom after uncoupling the 10 flexible pipe 22, so that if one of the members 10 or any of the parts carried thereby becomes broken or fails to operate properly, the member 10 and the parts which it carries may be readily lifted from the bearings 8 and another substituted for it, so that it will not be necessary to keep the car out of service during the repair or adjustment of the defective lubricating part.

When the temperature and character of 20 the oil or grease used as the lubricant are such that the oil is too thick to be drawn through the pipe 16 and sprayed into the guard 14 by the air passing through the pipe 17, a suitable electric heating unit 40 may 25 be employed in the box 13 and supplied with current through wires 41 from a suitable source to heat the oil to the proper temperature at which it will flow freely through the pipe 16.

30 I claim as my invention:—

1. In a device for oiling car wheel flanges and in combination, a support, a member movably mounted on the support and carrying an oil delivery part movable therewith 35 from an inoperative position away from a wheel flange to an operative position in close proximity to the flange, an oil carrying box carried by said member and acting by gravity to move the member and said part from 40 its operative position to its inoperative position, means adapted to be operated to move the member and said part from the inoperative position to the operative position, an oil pipe connecting said box and said part, and 45 an air pipe opening into the oil pipe, whereby when air is injected into the oil pipe it will draw oil from said box and feed it to said part.

2. In a device for oiling car wheel flanges 50 and in combination, a support, a member movably mounted on the support and carrying an oil delivery part movable therewith from an inoperative position away from a wheel flange to an operative position in close 55 proximity to the flange, an oil carrying box carried by said member and acting by gravity to move the member and said part from its operative position to its inoperative position, means adapted to be operated to move 60 the member and said part from the inoperative position to the operative position, an oil pipe connecting said box and said part, an air pipe opening into the oil pipe, whereby when air is injected into the oil 65 pipe it will draw oil from said box and feed

it to said part, and means to automatically close and open the air pipe when the member is moved to the inoperative and operative positions, respectively.

3. In a device for oiling car wheel flanges 70 and in combination, a support, a member movably mounted on the support and carrying an oil delivery part movable therewith from an inoperative position away from a wheel flange to an operative position in close 75 proximity to the flange, an oil carrying box carried by said member and acting by gravity to move the member and said part from its operative position to its inoperative position, means adapted to be operated to move the member and said part from the inoperative position to the operative position, an oil pipe connecting said box and said part, an air pipe opening into the oil pipe, whereby when air is injected into the oil 80 pipe it will draw oil from said box and feed it to said part, and a valve to control the passage of air through the air pipe, said valve comprising a movable body adapted to be moved to its open position by incoming air pressure within the air pipe when said member is moved to the operative position, and to be moved to its closed position by said member when it is moved to the inoperative position.

4. In a device for oiling car wheel flanges and in combination, a support, a member movably mounted on the support and carrying an oil delivery part movable therewith from an inoperative position away from a wheel flange to an operative position in close proximity to the flange, an oil carrying box carried by said member, an oil pipe connecting said box and said part, means adapted to be operated to move the member and said part from the inoperative position to the operative position, and an air pipe opening into the oil pipe, whereby when air is injected into the oil pipe it will draw oil from said box and feed it to said part.

5. In a device for oiling car wheel flanges and in combination, a support, a member movably mounted on the support and carrying an oil delivery part movable therewith from an inoperative position away from a wheel flange to an operative position in close proximity to the flange, an oil carrying box carried by said member, an oil pipe connecting said box and said part, means adapted to be operated to move the member and said part from the inoperative position to the operative position, an air pipe opening into the oil pipe, whereby when air is injected into the oil pipe it will draw oil from said box and feed it to said part, and means to automatically close and open the air pipe when the member is moved to the inoperative and operative positions, respectively.

6. In a device for oiling car wheel flanges 130

and in combination, a support, a member 5
movably mounted on the support and carrying
an oil delivery part movable therewith
from an inoperative position away from a
wheel flange to an operative position in
close proximity to the flange, an oil carrying
box carried by said member, an oil pipe
connecting said box and said part, means
adapted to be operated to move the member
10 and said part from the inoperative position
to the operative position, and a valve to con-
trol the passage of air through the air pipe,
said valve comprising a movable body
adapted to be moved to its open position by
15 incoming air pressure within the air pipe
when said member is moved to the operative
position, and to be moved to its closed position
by said member when it is moved to
the inoperative position.

20 7. In a device for oiling car wheel flanges
and in combination, a support, a member
movably mounted on the support and carrying
an oil delivery part movable therewith
from an inoperative position away from a
25 wheel flange to an operative position in
close proximity to the flange, an oil carrying
box carried by said member, means
adapted to be operated to move the member
and said part from the inoperative position
30 to the operative position, an oil pipe con-
necting said box and said part, an air pipe

carried by said member and opening into
the oil pipe, an air pipe carried by said
part, a flexible air pipe connecting the air
pipes carried by said member and said part,
and means to automatically close and open
35 one of said air pipes when said member is
moved to the inoperative and operative po-
sitions, respectively.

8. In a device for oiling car wheel flanges
and in combination, a support, a hollow oil
confining guard carried by the support and
adapted to embrace a wheel flange and be-
ing provided with spaced baffle walls there-
in, an oil delivery part opening into said
guard, and means to supply oil to the oil
45 delivery part.

9. In a device for oiling car wheel flanges
and in combination, a support, a hollow oil
confining guard carried by the support and
adapted to embrace a wheel flange and be-
ing provided with spaced baffle walls there-
in, said guard being movable from an inop-
erative position away from a wheel flange
50 to an operative position in close proximity
thereto, an oil delivery part opening into
said guard, and means to move the guard to
the operative position and to supply oil to
the oil delivery part.

In testimony whereof I affix my signature
hereto.

CHARLES T. BRADSHAW.
